UNITED STATES PATENT OFFICE.

MARSHALL SATTLEY AND ARCHIBALD SATTLEY, OF SPRINGFIELD, ILLINOIS,
ASSIGNORS TO THE SATTLEY MANUFACTURING COMPANY, OF SAME
PLACE.

CULTIVATOR.

SPECIFICATION forming part of Letters Patent No. 535,122, dated March 5, 1895.

Application filed October 18, 1894. Serial No. 526,248. (No model.)

To all whom it may concern:

Be it known that we, MARSHALL SATTLEY and ARCHIBALD SATTLEY, of Springfield, in the county of Sangamon and State of Illinois, 5 have invented certain new and useful Improvements in Cultivators, of which the following is a specification.

This invention relates to tongueless, balanced frame straddle row cultivators. It is 10 embodied in the structure hereinafter described and it is defined in the appended claims.

In the drawings forming part of this specification Figure 1 is a perspective representation of a cultivator constructed in accordance with our invention. Fig. 2 is a plan of one side of the front end of the cultivator. Fig. 15 3 is a rear elevation of so much of the cultivator as is shown in Fig. 2. Fig. 4 is a side elevation of a spindle-bearing draft plate, showing a draft bar in connection therewith.

The wheels 1 are journaled on spindles 2, which project from the sides of the vertical draft plates 3. The draft plates have hitch- 25 holes 3^a and also have inwardly turned lugs 3^b. The brackets, or frames, 9 have horizontal bearings at their forward ends, as indicated at 10. These bearings extend cross- 30 wise of the cultivator and receive the ends of arch 15. The bearings are slotted at 11, and pins 12 extend from the arch bar through the slots. Lugs 9^a are formed on the rear, outer corners of the brackets 9. They coincide with the lugs of plate 3, and the bolts 4 passing 35 vertically through both sets of lugs form pivoted connections between the bracket and the plates. The beams 14 connect with the brackets by vertical bolts which extend through heads 13 and through the brackets, 40 and provision is made for shifting the beams laterally so as to vary the distance between them. The draft bars are connected with the draft plates in a manner permitting a limited amount of vertical swing, and they are pro- 45 vided with single-trees 17.

The arch connects with the forward ends of the brackets some distance in advance of the wheel spindles and it inclines obliquely upward and forward to an extent sufficient to 50 practically balance the beams and their shovels, &c. To better provide for this result the

brackets may extend farther forward and be supplied with additional bearings for the arch, as suggested by dotted lines at 10^a in Fig. 2. This will enable the arch to be set forward or 55 back to correspond with the weight of the beams and shovels that may be used in any particular case. The slots 11 extend only short distances around the circumferences of the bearings, about one fourth, and the pitch of 60 the arch holds the pins, or at least one of them, always in contact with the front wall of the slot, where it, or they, holds the arch from pitching forward beyond its normal incline. By this provision the arch holds the brackets 65 against cross-wise tilting, the brackets hold the arch in its inclined position, and either beam may be raised and lowered independent of the other without affecting the inclination 70 of the arch.

The draft plate is pivoted, vertically, on the bracket. It carries the wheel spindle, and it provides for connection with the draft bar, as before specified. The connection of the draft bar with the plate is horizontally stiff, so that 75 when the team turns to one side the plate swings on bolt 4 and turns the wheel in the same direction.

In practical use the mechanism described is capable of producing desirable results, but 80 to keep the parts in position when the team is detached it is desirable that the wheels be held, yieldingly, at right angles with the transverse axes of the brackets. To effect this result we introduce springs arranged in a manner covered by us in a prior patent, but other arrangements may be substituted therefor 85 without departing from the principle of the invention.

The construction and arrangement of the 90 springs and adjuncts are as follows: The draft plate has pins, or bosses, 5 on opposite sides of its pivot. A head 6 bears against the bosses and has a rod extending across the bracket and through a hole in the upwardly extending lug 9^b. Spring 8 is placed on the rod, 7, between the lug and the head, and its tendency is to prevent the plate turning from its 95 shown position.

In the drawings, particularly in Fig. 4, the 100 draft plate is shown with hitch-holes in both front and rear edges. This is simply to per-

mit the one casting to be used on either side, and is a desirable, but not essential, feature.

Having thus described our invention, we claim as new and desire to secure by Letters

5 Patent—

1. In a cultivator of the class described, the combination of wheels, draft plates bearing rigidly extended spindles for the wheels, brackets hinged vertically to the draft plates 10 and extended forward thereof, an arch having horizontal bearings and a limited amount of rocking play in the front ends of the brackets, cultivator beams hinged vertically to the brackets, and draft bars having horizontally 15 stiff connections with the draft plates and vertical play, substantially as set forth.

2. In a cultivator of the class described, the combination of wheels, draft plates bearing rigidly extended spindles for the wheels,

brackets hinged vertically to the draft plates 20 and extended forward thereof, an arch having horizontal bearings and a limited amount of rocking play in the front ends of the brackets, cultivator beams hinged vertically to the brackets, draft bars having horizontally stiff 25 connections with the draft plates and vertical play, and springs acting between the brackets and the draft plates and tending to hold the wheel spindles at right angles with the brackets, substantially as set forth. 30

In testimony whereof we sign our names in the presence of two subscribing witnesses.

MARSHALL SATTLEY.
ARCHIBALD SATTLEY.
